UNITED STATES PATENT OFFICE.

CARL F. JOHNSON, OF MILWAUKEE, WISCONSIN, ASSIGNOR TO JOHNSON SERVICE COMPANY, OF MILWAUKEE, WISCONSIN, A CORPORATION OF WISCONSIN.

SCREW-THREADED FASTENING.

1,300,275.

Specification of Letters Patent. Patented Apr. 15, 1919.

Application filed September 3, 1914. Serial No. 860,047.

To all whom it may concern:

Be it known that I, CARL F. JOHNSON, a citizen of the United States, residing at Milwaukee, in the county of Milwaukee and 5 State of Wisconsin, have invented certain new and useful Improvements in Screw-Threaded Fastenings, of which the following is a specification.

This invention relates to screw threaded 10 fastenings and particularly to a screw having a novel driving contact, so formed and so related to the object held by the screw that the latter may be removed only by means of a special key or wrench provided 15 for the purpose.

The object of the invention is to provide 20 a device of this class which is peculiarly difficult to turn with any implement other than the special wrench provided for the purpose, and which at the same time shall be simple and inexpensive.

Broadly stated the invention involves a 25 screw having a circular head which lies in a countersunk recess in the object held by the screw, such recess being only slightly 30 larger in diameter than the head of the screw. The difference in diameter is only sufficient to permit the insertion of the thin 35 annular flange of a circular socket wrench, which enters into locking engagement with the screw by means of an eccentric longitudinal pin. The counter-sinking of the 40 head prevents the releasing of the screw by means of pliers, while the use of a single and only slightly eccentric opening in the 45 head prevents the use of this as the sole means of turning the screw. It is possible by careful proportioning of the parts to produce a screw which can be removed only 50 with the specially designed wrench which accurately fits the screw head.

Preferred embodiments of the invention are illustrated in the accompanying drawing, in which:—

45 Figure 1 is an axial section through a screw embodying my invention, showing the same in position with the wrench applied;

Fig. 2 is a section on the line 2—2 of Fig. 1;

50 Fig. 3 is a view partly in longitudinal section and partly in elevation, showing the screw and wrench separated from each other;

Fig. 4 is a perspective view of the screw and wrench; and

Fig. 5 is a view similar to Fig. 3 illustrating a slightly modified form of the device.

Referring to Figs. 1 to 4 of the drawings, 6 and 7 represent two separate pieces which are held together by the screw. The piece 60 6 is provided with a countersunk aperture 8 and the piece 7 with a threaded hole 9 to receive the threaded portion 10 of the screw. The head 11 of the screw is cylindrical in shape and is preferably slightly rounded at 65 its upper edge 12, in order to prevent the successful use of a taper socket wrench or the like, as this will not hold so well on a rounded surface as on a sharp edge.

A longitudinal hole 13 which is eccentric 70 with respect to the axis of the screw extends from the head 11 to the end of the threaded portion of the screw. It is not essential however that this hole extend the entire length of the screw provided it is given sufficient depth to receive the wrench pin and hold the same firmly. When the screw is in place the head 11 lies wholly within the countersunk recess 8 of the piece 6, only a 75 very small annular space intervening between the screw head and the sides of the recess. To turn the screw, I make use of a wrench having a stem 14 and a cylindrical socket 15 whose annular rim extends into the space between the sides of the head 11 80 and the walls of the countersunk recess 8. This wrench carries an eccentric longitudinal pin 16 the eccentricity of the pin 16 being the same as that of the hole 13 of the screw and when the wrench is applied to the 85 screw head the pin 16 is the means by which the screw is turned. The wrench may be provided with a milled head 17 or any other suitable means for turning it.

In Figs. 1 to 4 the invention is illustrated 95 as applied to a very small machine screw, the drawing being on an enlarged scale. The device has a particular advantage in small size screws because the screw has sufficient frictional engagement with the pin 16 to be 100 held thereby so that a ready means of holding the screw during insertion is provided.

In Fig. 5, I illustrate the device as applied to a button head screw, or other screw having a substantially hemispherical head. 105 These screws, like the ones shown in Figs. 1

to 4, are preferably mounted in countersunk holes and for similar reasons, but as the hemispherical head offers very little opportunity for the use of pliers or taper socket wrenches, this latter form is sometimes preferable where extreme safety against removal is necessary. Obviously the form shown in Fig. 5 need not be so deeply countersunk as that shown in Figs. 1 to 4. Corresponding parts in Fig. 5 are numbered similarly to those in Figs. 1 to 4, and detailed explanation is unnecessary. The pin 16 is comparatively short in the embodiment shown in this figure, but obviously it may be made any desired length by setting it closer to the center as in the preferred form of the invention.

Referring more particularly to Figs. 1 to 4, it will be noted that the pin 16 is placed 20 in direct shear and therefore need not be very heavy. Similarly as the flange 15 is in contact with the head 11 all around the same it too can be made relatively thin, so that only a very slight space between the head 11 25 and the sides of the countersunk recess 8 is necessary. Consequently, and this is particularly true in the smaller sizes, there is no opportunity for the insertion of pliers or other clamping devices while the hole 13 may 30 be made so small that it offers no adequate means for turning the screw except by means of the particular type of wrench illustrated and so proportioned as to fit the screw accurately. In other words the parts may be so 35 nicely proportioned that only a closely fitting key will have strength sufficient to turn the screw.

The embodiment shown in Fig. 5 may be similarly designed.

40 Having thus described my invention, what I claim is:—

1. As a new article of manufacture, a screw having a threaded body and a driving end portion of substantially circular contour, said driving portion provided with one 45

and only one longitudinal hole located eccentrically with reference to the axis of the screw.

2. The combination of a screw having a single longitudinal hole eccentric with respect to the axis of the screw, and having a driving end portion of circular contour; and a removable driving key therefor, having an eccentric pin adapted to enter the hole in said screw, and having a circular projection adapted to mate with the driving end portion of the screw to hold the screw and key in axial alinement. 55

3. The combination of a member having a threaded hole; a member having a countersunk hole; a screw holding said members together and having a head lying substantially entirely within said countersink and nearly but not quite filling the same in the direction of its diameter, said screw having a single 60 eccentric hole in its exposed end; and a turning key having a thin flange adapted to embrace the head of said screw within said countersink and having an eccentric pin adapted to enter the hole in said screw. 65

4. In combination with a body having a screw seat, the outer portion of which seat is of slightly larger diameter than the screw it is to receive; a screw adapted to fit and fill the lower or inner portion of said seat but 70 to leave an annular space about its outer or head portion, said screw having an eccentric hole or socket parallel with its longitudinal axis; and an implement for turning said screw, having an annular rim or flange to fit 75 the screw-head and occupy the annular space about said head, and having also an eccentric pin to enter the hole or socket in the screw.

In testimony whereof I have signed my name to this specification in the presence of 80 two subscribing witnesses.

CARL F. JOHNSON.
